UNITED STATES PATENT OFFICE.

RICARDO BLASQUEZ DURÁN, OF TORREON, MEXICO.

SUPPORT FOR ELECTRIC WIRES.

1,177,400.

Specification of Letters Patent. Patented Mar. 28, 1916.

Application filed December 30, 1912. Serial No. 739,250.

To all whom it may concern:

Be it known that I, RICARDO BLASQUEZ DURÁN, a citizen of the Republic of Mexico, and a resident of Torreon, in the State of Coahuila, Mexico, have invented a new and Improved Support for Electric Wires, of which the following is a full, clear, and exact description.

My invention has for its object to provide a support for electric wires, which makes the use of an auxiliary supporting cable unnecessary, while, at the same time, doing away with all danger from broken or fallen electric wires.

Briefly my invention consists of wire supports, with pivoted conducting arms, to which the terminals of the wire sections are secured, the conducting arms being held in electrical communication with central conductors, by the wire sections, when the wires are in normal position. However, when a wire section is broken or falls, the weight of the wire will move the arm out of electrical communication with the central conductor, so that the fallen wire will not endanger pedestrians.

Another object of the invention is to prevent the wearing of the wire sections at their supports.

Still other objects of the invention will appear in the following complete specification, in which the preferred form of the invention is disclosed.

In the drawings similar characters of reference indicate corresponding parts in all the views, in which—

Figure 1 is a side elevation of my invention, showing parts in section; Fig. 2 is a side elevation, similar to that shown in Fig. 1, but with the conducting arms moved so that there is no longer an electrical communication with the conductor of the central wire support; Fig. 3 is a plan view of Fig. 1; Fig. 4 is a sectional view on the line 4—4 of Fig. 1; and Fig. 5 is a sectional view on the line 5—5 of Fig. 1.

By referring to the drawings it will be seen that a non-conducting member 5 is provided, to the bottom of which there is secured a conducting shoe 6, which is spaced from the ends 7 of the non-conducting member 5, and extending therefrom there are arms 8, these arms 8 being provided in two pairs, a lever 9 being fulcrumed between each pair of arms. These levers 9 are constructed of conducting material, and they

are provided with caps 10, which serve as switch movers and which are adapted to engage the projecting switch pieces 11 on the conducting members 12, secured to the top of the non-conducting member 5, at its opposite ends. The conducting members 12 are connected electrically with the conducting shoe 6, by means of the insulated conducting wires 13, which are secured to the conducting members 12, and the conducting shoe 6 in the customary manner. It will therefore be seen that when the levers 9 are in normal position, as shown in Fig. 1 of the drawings, a current may pass from one of the arms through the cap 10 to the switch piece 11 of the conducting member 12, through one of the conducting wires 13, to the conducting shoe 6, and then through the other conducting wire 13 to the other conducting member 12, and to the other lever 9. Each of the levers 9 has a groove 15 at its under side, and extending to its free end. In each of these grooves there is disposed a wire 16, the wire 16 extending through an opening 17 to the top of the arm 14, the wire 16 being engaged by a screw 18, which meshes in a threaded orifice 19 extending to the opening 17. In this way the wires 16 are secured to the arms 14 of the levers 9, and as the wires 16 are normally disposed horizontally, as shown in Fig. 1 of the drawings, they serve to hold the levers in such a position that the switch caps 10 engage the switch members 11, so that the current may pass through the right lever 9, and through the parts which have been described, to the left lever 9, to the wires 16 at the left of the wire support. In order to permit the trolley wheel which may engage the wires 16 and the shoe 6, to pass readily from the bottom of one of the levers 9 to the conducting shoe 6, I provide the bottom of the non-conducting member 5 at its opposite ends, with metal shoes 20, which receive the trolley wheel as it leaves the bottom of one of the levers 9, and conducts the trolley wheel from one of the levers 9 to the conducting shoe 6. Secured to the top of the non-conducting member 5 there is a saddle 21, which has a spindle 22, on which is mounted laterally extending arms 23, these laterally extending arms 23 having orifices 24, to which may be secured wires or other supporting means. There are also eye members 25, which are secured one at each side of the non-conducting member 5, and below the

saddle 21, these eye members 25 serving as additional means for holding the wire support in position.

It will be seen by referring to Fig. 2 of the drawings, that when a trolley wheel 26 passes from one wire or cable 16, to the other wire or cable 16, it will not wear the wires at the points where they are connected to the supporting member. This is so for when the trolley wheel 26 leaves one of the levers 9, and strikes the conducting shoe 6, thereby raising the conducting shoe, the levers 9 will have a movement relatively to the conducting shoe 6, which will prevent the wearing of the parts.

Having thus described my invention, I claim as new and desire to secure by Letters Patent:

1. In a support for electric wires, a member having a conductor and a concave end, an arm extending from the concave end of the member, an electrically conducting lever fulcrumed to the arm and having an arm normally contacting with the conductor, and a heel normally disposed adjacent the bottom of the end of the member and adapted

to move in the concave portion of the member when the arm of the lever moves away from the conductor.

2. In a support for electric wires, a non-conducting member, conducting members spaced from each other and secured to the top of the non-conducting member, switch pieces on the conducting members extending upwardly, a conducting shoe on the bottom of the non-conducting member, wires connecting electrically the conducting members with the conducting shoe, arms extending from the ends of the non-conducting member, levers fulcrumed to the arms and having upwardly extending arms with caps normally extending over the conducting members to rest on the switch pieces, the levers having additional arms to which wires may be secured.

In testimony whereof I have signed my name to this specification in the presence of two subscribing witnesses.

RICARDO BLASQUEZ DURÁN.
